SNACK SERVING TRAY OR THE LIKE

Robert Karoff, 222 4th Ave., New York, N.Y.

Filed July 23, 1959, Ser. No. 56,891

Term of patent 3½ years

(Cl. D44—10)

I claim:

The ornamental design for a snack serving tray or the like, substantially as shown and described.
